US00D969783S

(12) **United States Design Patent** (10) Patent No.: **US D969,783 S**
(45) Date of Patent: **** Nov. 15, 2022**

(54) **HEADPHONES**

(71) Applicant: **Apple Inc.**, Cupertino, CA (US)

(72) Inventors: **Shota Aoyagi**, San Francisco, CA (US);
Robert Boyd, Los Angeles, CA (US);
Robert Brunner, Glen Ellen, CA (US);
Monica Fernandez, Reseda, CA (US);
Christopher Kuh, San Francisco, CA (US);
Christopher J. Stringer, Woodside, CA (US)

(73) Assignee: **Apple Inc.**, Cupertino, CA (US)

(**) Term: **15 Years**

(21) Appl. No.: **29/824,302**

(22) Filed: **Jan. 24, 2022**

Related U.S. Application Data

CLAIM

The ornamental design for headphones, as shown and described.

DESCRIPTION

FIG. 1 is a front perspective view of headphones showing the claimed design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines in the figures show portions of the headphones that form no part of the claimed design.

1 Claim, 5 Drawing Sheets
